[57] CLAIM

The ornamental design for an automobile, as shown and described.

DESCRIPTION

FIG. 1 is a front elevational view of an automobile showing my new design;

FIG. 2 is a rear elevational view thereof;

FIG. 3 is a left side elevational view thereof;

FIG. 4 is a top plan view thereof;

FIG. 5 is a front and left side perspective view thereof;

FIG. 6 is a rear and left side perspective view thereof; and, FIG. 7 is an enlarged fragmented front and left side perspective view thereof, similar to FIG. 5.

The right side of the automobile, not shown, mirrors the left side.
